ELECTRIC GLOW DISCHARGE AMPLIFYING TUBE

Application filed February 24, 1931, Serial No. 517,953, and in Germany March 17, 1930.

This invention relates to glow discharge amplifying tubes in which a discharge takes place between two electrodes in such a manner that electrons are drawn from the said discharge space into a second dark amplifying space which contains, in addition to one or more grids, a second anode, a so-called amplifying anode. Applicants have previously proposed to construct the first anode, viz. 5 the discharge anode, in such a manner that it shall interrupt the straight line connections between the cathode and the controlling electrode which is provided between the first and the second anode, so that the current flowing 10 to the second anode shall mainly proceed from the outer parts of the glow discharge lying in the proximity of the edge of the first anode. This connection is further improved by the arrangement according to the present invention.

According to a physical law an ionization by a movable electron after an impact with an atom of gas could again be effected only if the electron has traversed a path which 25 corresponds at least to the so-called "free path" and has thereby attained a speed of 25 volts. On the other hand, if the electron can traverse only a smaller path, no ionization takes place. In the vacuum industry, this law is utilized, for instance in connection with glow discharge rectifying tubes without a controlling electrode, by making the distance between the anode and cathode very small at certain points as, in 30 that case, in spite of the small path, no transition of current can take place for the reasons which have been stated.

In the present invention, the physical law above referred to is utilized for better localizing the discharge between the cathode and the first anode.

It is true that in this case the decrease should not be carried out to such an extent that a glow discharge no longer can take 45 place between these two electrodes, as in that case no source of electrons for the amplifying current would be available. However, although in view of the fact that the individual parts of the discharge anode have a larger 50 surface than the parts of the cathode lying

behind them, only the smallest distances between the cathode and the discharge anode come to lie within the free path, it is possible to prevent a discharge from the cathode, which may for instance be in the form of a wire, only in an approximately perpendicular direction with respect to the discharge anode, whilst a discharge takes place towards the edges of the discharge anode where the distances from the cathode are greater. In 55 this way the glow discharge is localized at the points where the same is utilized for the amplification current, that is to say towards the edges or the points of interruption of the discharge anode.

The accompanying drawing illustrates, in plan view, one form of construction of the glow discharge amplifying tube according to the invention, the arrangement being shown on an enlarged scale for the sake of clearness. The system of electrodes consists of four concentric electrodes. The outermost electrode, viz. the cathode k , consists of a plurality preferably four, wires, which are parallel to the axis of the tube. The next inner electrode, the discharge anode a_1 , consists of the same number of strips parallel to the axis of the tube which belong to a cylindrical surface and each one of which is arranged opposite the individual wires of the cathode in such a manner that they screen the said wires with respect to the controlling electrode s and the amplifying anode a_2 . The distances between k and a_1 are made so small that the central parts of a_1 , which are at the smallest distances from k , lie below the free path, so that the discharge takes place towards the edges of the individual strips of a_1 . According to the gas pressure, such an effect will be secured for distances ranging between half and one millimeter. The amplifying anode a_2 passes through the centre of the system of electrodes and it is surrounded by 85 a helical controlling electrode s . The distances between a_2 and a_1 and between a_2 and s are also smaller than the length of the free path. As previously proposed by the applicants, the electrodes are mounted on a 90 100

foot f of insulating material, which is supported on the base of the glass tube r .

The gas pressure in the tube can thereby be reduced from about 4 mms. to about 1 mm.

5 The arrangement according to the present invention is especially suitable also for such tubes which are intended to be used in connection with resistance coupling. As in such a case the use of a large anode current is not important, the gas pressure can be substantially reduced, so that it is possible to increase the anode voltages and also to decrease the grid current which hitherto was not possible to be entirely avoided.

10 15 15 What we claim is:—

1. A gas filled glow discharge tube for amplifying, detecting and generating alternating electric currents, comprising a cathode, a first anode, a second anode mounted behind said first anode outside the space between said cathode and said first anode, and a controlling electrode mounted between said first and said second anode, the area of said first anode being greater than that of said 20 cathode so that said first anode acts as a screen between said cathode and said controlling electrode, the minimum distance between said cathode and said first anode being not greater than the mean free path of 25 the gas and the distance between said cathode and the edges of said first anode being greater than the mean free path of the gas, so that a glow discharge takes place from 30 said cathode only to the edges of said first 35 anode.

2. A gas filled glow discharge tube for amplifying, detecting and generating alternating electric currents, comprising a cathode, a first anode, a second anode mounted 40 behind said first anode outside the space between said cathode and said first anode, and a controlling electrode mounted between said first and said second anode, the area of said first anode being greater than that of 45 said cathode so that said first anode acts as a screen between said cathode and said controlling electrode, the minimum distance between said cathode and said first anode being not greater than the mean free path 50 of the gas and the distance between said cathode and the edges of said first anode being greater than the mean free path of the gas so that a glow discharge takes place from 55 said cathode only to the edges of said first anode, the gas pressure of said tube being about 1 millimetre.

In testimony whereof we have signed our names to this specification.

GEORG SEIBT.

HELLMUTH BLEY.
